UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPET.

SPECIFICATION forming part of Design No. 12,129, dated January 18, 1881.

Application filed September 22, 1880. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design is composed, mainly, of an aggregation of angular figures, A B C b c d e, and partially-angular figures a, all inclosed by variously-formed borders, and ornamented by various designs, the most prominent feature of the ornamentation being clusters of narrow elongated sharply-pointed leaves, which in most cases project beyond the figures on which they rest, the leaves of each cluster diverging from a common center.

The design also consists in the Japanese-fan-shaped figures D, surrounded by the figures A B C b c d e.

I claim as my invention—

1. The design for a carpet, consisting of figures ornamented by clusters of narrow elongated sharply-pointed diverging leaves, substantially as shown.

2. The design for a carpet, consisting of the figures A B C D a b c d e, substantially as shown and described.

THOMAS J. STEARNS.
